UNITED STATES PATENT OFFICE.

GEORGE W. HEATH, OF NEWARK, NEW JERSEY.

PEN-CLIP.

1,145,584.

Specification of Letters Patent.

Patented July 6, 1915.

Application filed February 6, 1914. Serial No. 816,880.

To all whom it may concern:

Be it known that I, GEORGE W. HEATH, a citizen of the United States, residing in the city of Newark, county of Essex, and State 5 of New Jersey, have invented certain new and useful Improvements in Pen-Clips, of which the following is a specification.

My invention relates to improvements in spring clips for holding pencils, pens, thermometers and the like in the pocket and the invention particularly resides in the means 10 for fastening the clip to the article.

It is of primary importance to make such articles as reservoir pencils, fountain pens 15 and the like with a minimum diameter or thickness and at the same time to provide as large a space therein as possible in order to accommodate the inserts, such as the pencil feeding devices, and ink reservoirs, with the 20 largest possible capacity so that there is but little, if any, available space for the fastening of the clip. It has been suggested to fasten the clip entirely on the outside of the article as by means of an encircling spring 25 band, but this has the disadvantage of working loose and is seldom secure in position. Where the fastening means of the clip is extended through the outer wall of the article, the projections therein have either reduced 30 the possible diameter of the insert or formed a projection which caught the end of the insert as it was positioned in the casing or barrel.

One of the objects of the invention is to 35 securely fasten the spring clip in position on the article so as not to appreciably increase the diameter of the same and to provide a smooth, internal bore of the greatest possible diameter.

As these articles are frequently made of 40 one of the precious metals, the casings are usually made of very thinly rolled metal and accordingly it is a further object of the invention to securely fasten the clip to this 45 thin material without the use of any reinforcement to take up torsional strains.

Various other objects and advantages of 50 the invention will be in part obvious from an inspection of the accompanying drawings and in part will be more fully set forth in 55 the following particular description of one form of mechanism embodying the invention and the invention further consists in certain new and novel features of construction and combination of parts hereinafter set forth and claimed.

Referring to the accompanying drawings:

Figures 1, 2 and 3 are sectional views taken axially through the upper portion respectively of a fountain pen, a reservoir pencil 60 and a clinical thermometer, each showing a preferred embodiment of my invention in position thereon. Fig. 4 is an enlarged section showing the details of the connection on a thin barrel. Fig. 5 is a view similar 65 to Fig. 4 showing a thick barrel; and Fig. 6 is a plan view of the clip detached from the barrel.

In the drawings is shown an outside tubular casing or barrel 1, such as the inclosing 70 caps, constructed preferably of some thin metal, such as rolled gold, within which barrel is adapted to be positioned the pen proper 2, feeding barrel 3, thermometer bulb 41 or other insert having a cross-section 75 which may be equal to that of the bore. Affixed to the barrel is an integral spring clip 4 which may be of any of the convenient designs, comprising a free end 5 for engagement with the pocket and a relatively broad 80 base 6 conforming substantially to and fitting the curvature of the barrel. A prong 7 extends from the end of the base 6 and is bent transversely into a position at right angle to the length of the clip. A second 85 prong 8 is cut from the base 6 and bent therefrom parallel to the prong 7 leaving an aperture 9 centrally in the base 6. By means of suitable stamps a portion of the initial of the barrel 1 is pressed outward to form an 90 internal recess 10 of a depth at least equal to the thickness of the prongs 7 and 8. The base 6 is laid on the projecting portion of the barrel with the prongs inserted respectively in slots 11 and 12 and by means of a closely 95 fitting mandrel the inner ends of the prongs are pressed longitudinally into the recess 10, leaving the interior of the barrel free from projections. Especially with the thin metal, the action of this rod tends to bulge the 100 metal of the barrel adjacent the aperture 9 into this aperture thus interlocking the barrel with the clip.

By means of a construction of this character the clip is fastened to the barrel at a 105 plurality of points longitudinally and each fastening extends over a relatively broad engagement thereby eliminating any tendency to break under lateral strains. The lapping inner ends of the prongs maintain 110 the continuity of the barrel and this means of connection strengthens rather than weakens the resistance of the barrel to crushing strains at this point. There is no soldering

or other heating means for connecting the parts which might injure the appearance of the metals used the entire process of attaching the parts being mechanical.

5. It is of course obvious in those cases where the barrel is made of some relatively thick material as rubber compound shown in Fig. 5, that the recess 10 may be formed by suitably milling the inner wall of the bore with 10 out pressing the material outward and there is thus maintained the uniformity of configuration to the outside of the barrel and the inner bore is freed of any projections.

Having thus described my invention, I 15 claim:

1. In a device of the class described, the combination with a tubular barrel having a preformed recess therein and having a plurality of spaced slots through the recessed 20 portion, of an integral clip having a pocket engaging free end and means adjacent the other end for fastening the same to the barrel at the recessed portion thereof, said means including angled prongs extending 25 through said slots with the ends thereof disposed entirely within said recess, whereby the bore of the barrel is free of any projection.

2. In a device of the class described, the 30 combination with a barrel having a slot therein, of a clip having an opening therein and a prong adjacent said opening positioned in said slot, a portion of said prong being pressed against said barrel and a portion 35 of said barrel pressed within said opening to hold said barrel in engagement with said clip.

3. In a device of the class described, the 40 combination of a tubular barrel of relatively thin metal having an inner bore of uniform cross-section adapted to contain an insert having a cross-section equal to that of the bore and a clip having parts extending through said barrel and engaging the 45 same on the inner side thereof.

4. The combination with a barrel of a fountain pen having a raised portion forming a recess within the barrel, said portion having a plurality of apertures there- 50 through, of a unitary spring clip having means integral therewith adjacent one end thereof for fastening the same to the outside of the barrel, said means comprising a flexible prong adjacent the fastened end of the 55 clip and upset in one of said apertures and a second prong bent from the clip intermediate its sides and upset in another of said apertures; the portion of said prongs within the barrel being within said recess 60 whereby projections within said barrel are eliminated.

5. The combination with a tubular barrel of relatively small bore having a portion 65 adapted to have a clip affixed thereto, said portion having a plurality of apertures extending therethrough, of a unitary spring clip having means integral therewith adjacent one end thereof for fastening the same to the outside of the barrel, said means comprising a flexible prong adjacent the fastened end of the clip and upset in one of 70 said apertures and a second prong bent from the clip intermediate its sides and upset in another of said apertures, said prongs both extending in the same direction and firmly 75 engaging the inner surface of the barrel to reinforce the portion thereof having the apertures.

6. In a device of the class described, the combination with a tubular member having 80 a pair of spaced apart apertures therein, of a one-piece sheet-metal clip relatively thin compared to its other dimensions, said clip having a relatively broad base portion 85 adapted to conform to the outside of the member adjacent the apertures and having a pocket engaging portion forming a substantially straight prolongation of said base, with a portion thereof adjacent the base 90 adapted to be spaced from the adjacent portion of the member to form a space therebetween, said base having a plurality of prongs integral therewith and bent therefrom, one for each aperture, the distance 95 between the bent prongs being substantially equal to the distance between adjacent edges 100 of the apertures, said prongs extending through the apertures, having a tight fit therein and adapted to be bent within the member to fasten the clip in position.

7. A pen clip forming an article of manufacture adapted to be fastened to a fountain pen barrel, said clip comprising a one-piece sheet of spring metal relatively thin compared with its other dimensions having a 105 base adapted to conform to the configuration of the outer surface of the barrel and having a pocket engaging member forming a substantially straight prolongation of said base, said base portion having a plurality of prongs integral therewith and adapted to be bent from the general plane 110 of the base and pocket engaging member to fasten the clip to the pen barrel, one of said prongs being an extension from an outer 115 edge of said base.

In witness whereof I have hereunto set my hand in the presence of two witnesses.

GEORGE W. HEATH.
